UNITED STATES PATENT OFFICE

ERNST TREIBMANN, OF LEIPZIG, GERMANY

ELECTRODE FOR UNIPOLAR HIGH-FREQUENCY CURATIVE TREATMENT

Application filed October 12, 1928, Serial No. 312,017, and in Great Britain July 17, 1928.

This invention relates to a combination electrode intended for unipolar high-frequency curative treatment and by means of which the action on the part of the body under treatment can be exerted on several sides at once. A feature of the invention is that the combination electrode, composed of a plurality of electrodes, which may be of different character consists in a holder which is springy, or made of elastic material and is also provided with interchangeable members.

The holder is connected, on the one hand, with the handle of the apparatus, and carries the several electrodes intended for application to the body, said electrodes forming, in this case, a multiple electrode which adapts itself automatically to the contour of that portion of the body which is under treatment for the time being.

The hitherto known high-frequency appliances mainly comprise single elongated glass electrodes mounted direct in the handle.

It has now however been ascertained that a more intensive action on the deep-seated organs of the body can be obtained by employing, in place of a single electrode as heretofore, a plurality of electrically interconnected electrodes conjointly. This furnishes a combination electrode in accordance with the invention, with which the high-frequency waves from the several attachments penetrate deeply and supplement and intensify each other.

It should also be borne in mind that the heating of the part of the body under treatment is not so intensive with such a combination electrode, in consequence of which a longer treatment can be given, this in turn having a special curative effect in the case of many illnesses.

In order more clearly to understand the invention, reference is made to the accompanying drawings, which illustrate by way of example several embodiments thereof.

Fig. 1 of said drawings, shows an assembled electrode, consisting of the lug *a*, the bow *b* and the mount *e* in which latter the electrodes *f* are secured. The bow *b* is de-

tachable from the lug *a*, which serves for the attachment of the handle, and may be replaced by one or more bent or flattened bows as shown in Figs. 4 and 5.

Fig. 2 is a lateral section and Fig. 3, a plan, of the mount *e*.

The mount *e* is slidably arranged on the bow *b*, and can be secured thereto by the screws *e'*. Said mount is provided with a slit portion *g* which is surrounded by a clip *h*, which, after the introduction of the glass electrode *f*, is tightened by means of a screw *i* so that the electrode *f* is securely held in the mount.

Fig. 6 is a plan of Fig. 4.

Fig. 7 is a side elevation, Fig. 8 a cross section along the line 8-8 of Fig. 7, and Fig. 9 a plan of a combination electrode in which the holder *k* is of insulating and extensible material, such as rubber, and can be attached to the body. On the side remote from the body, the holder *k* is provided with contact springs *l* for interconnecting the electrodes *f*.

The contact springs *l* adjust themselves automatically, so that the electrodes are in contact and connection in any position. In order to prevent the electrodes from slipping off the contact, this latter may be given the cross-section shown in Fig. 8. The holder *k* is provided with holes *m*, into which electrodes can be inserted at varying intervals.

It is obvious that various modifications and alterations may be made without departing from the invention which broadly resides in the provision of a combination electrode for unipolar high-frequency curative treatment consisting of a plurality of electrodes (which may be of different kinds) which are mounted in a holder which is springy or made of elastic material.

I claim:—

1. In an apparatus for unipolar high frequency curative treatment, a deformable holder of insulating material, a plurality of electrodes mounted on said holder and spring means electrically interconnecting said electrodes.
2. In an apparatus for unipolar high fre-

5 frequency curative treatment, a deformable holder of insulating material a plurality of electrodes mounted on said holder extensions on said electrodes, spring means electrically interconnecting said extensions and means guiding said extensions in said spring interconnecting means.

10 3. In an apparatus for unipolar high frequency curative treatment, a deformable holder of insulating material a plurality of electrodes mounted on said holder, means securing said holder to the body and spring means mounted on said holder at the side remote from the body and adapted electrically to interconnect said electrodes.

15 4. In an apparatus for unipolar high frequency curative treatment, a deformable holder composed of a plurality of interchangeable parts, a lug on said holder, a handle adapted to fit on said lug, a plurality of sleeve members slidably mounted on said holder, means for tightening up said sleeve members on said holder and electrodes insertable in said sleeve members.

20 5. In an apparatus for unipolar high frequency curative treatment, a deformable holder composed of a plurality of interchangeable parts, means securing said holder to the body, sleeve members slidably mounted on said holder, means for tightening up said sleeve members on said holder, electrodes insertable in said sleeve members, and spring means mounted on said holder at the side remote from the body and adapted electrically to interconnect said electrodes.

25 6. In an apparatus for unipolar high frequency curative treatment, a curved deformable holder composed of a plurality of interchangeable parts, means securing said holder to the body, sleeve members slidably mounted on said holder, means for tightening up said sleeve members on said holder, electrodes insertable in said sleeve members, extensions on said electrodes, spring means mounted on said holder at the side remote from the body and adapted electrically to interconnect said extensions on said electrodes and means guiding said extensions in said spring interconnecting means.

In testimony whereof, I affix my signature.
ERNST TREIBMANN.
